UNITED STATES PATENT OFFICE

JOHN EKERN OTT, OF CHICAGO, ILLINOIS, ASSIGNOR TO ACME STEEL COMPANY, OF CHICAGO, ILLINOIS, A CORPORATION OF ILLINOIS

STRAP SEAL AND METHOD OF FORMING THE SAME

Application filed January 23, 1932. Serial No. 588,817.

This invention relates to strap seals and its purpose is to provide an improved sealing joint for uniting the overlapping ends of a metallic strap such as is commonly employed for reenforcing packages or for securing together a plurality of packages or the like. The present invention is an improvement upon the seal joint which is described and claimed in the United States patent to Ralph H. Norton No. 1,260,016, dated March 19, 1918.

This strength may be obtained by changing the shape of the deformation, but, while it is found that some width of the cut or other deformation is most suitable for each width of the strap, there is no possibility of increasing the strength of the joint to approximate that of the strap merely by selecting the most favorable width or shape of cut or deformation in combination with the most favorable depth of the cut or deformation. 55

In said prior patent there is disclosed a strap seal of sleeve-like form through which the overlapping ends of a metallic strap are threaded and the edges of the strap and seal are then bent and sheared transversely to cause portions of the strap and seal at the edges of the cuts formed by the shearing action to abut against each other and form an interlocking joint. While a seal of this type forms a very strong and secure joint, it has been found in practice that the strength of the joint is considerably less than that of the steel strap which has its ends secured together by the joint and when a failure has occurred it has uniformly occurred at the joint due to the weakening of the strap at this point. It has been found that the strength of the binder as a whole may be increased by decreasing the depth of the cut or other deformation of the edges, that is, the extent to which the cut formed by the shearing action or other deformation extends inwardly from the lateral edges of the seal and strap but this increase takes place only within certain limits and a marked decrease is noted as the depth of the cut or other deformation approaches zero so that the maximum strength which is obtainable by adjusting the depth of the cut or deformation to the most suitable proportions, as compared with the width of the strap, is only 70% or 75% of the strength of the strap. It has also been discovered that some variation in the strength of the joint may be effected by varying the width of the cut or other deformation, that is, for example, the distance between two parallel cuts formed by the shearing action, as disclosed in the drawings of said Norton patent, and also that some variation in

The present invention obtains the object referred to above by providing a strap and seal with a plurality of separate pairs of deformations formed preferably by separate shearing actions at a plurality of points 65 along the length of the seal and it has been found that by the present invention a strap seal may be obtained which has a strength approximating that of the uncut strap. According to the present invention, the opposite edges of the seal and overlapping ends of the strap are sheared or deformed at a plurality of points along their length to form a plurality of deflected lugs and a pair of interlocking shoulders at the edges of each 70 lug. In practicing this improvement in the formation of a seal joint, the depth of the cut or deformation inwardly from the edges of the seal is preferably varied from one side of the deformation to the other so that its inner margin is directed at an angle to the longitudinal axis of the strap. The arrangement of the deformations is also preferably such that the angles of the inner margins of some of the deformations 75 are directed oppositely to the angles of the inner margins of the other deformation on the same side of the seal and strap. With this arrangement, it is found that although the strength of the joint at the bottom of 80 one cut or deformation may be only 60% of that of the strap, the provision of other similar cuts or deformations serves to increase the composite strength of the joint as a whole so that it very closely approaches the strength of the uncut strap. The best results are ordinarily obtained by increasing the width of each deformation, measured longitudinally of the strap, as the width of the strap increases. These and 85 90 95 100

other features of the invention will be more clearly understood from the succeeding discussion of the principles of the invention.

The nature of the invention will be understood from the following specification taken with the accompanying drawings, in which one example of the improved seal and one method of forming the same are illustrated. In the drawings,

10 Fig. 1 shows a top plan view of the overlapping ends of a metallic strap united by a seal embodying the principles of the present invention and employing three deformations along each side of the seal;

15 Fig. 2 shows a side elevation of the strap ends and seal illustrated in Fig. 1;

Fig. 3 shows an enlarged transverse section on the line 3—3 of Fig. 1;

20 Fig. 4 shows a top plan view of another embodiment of the invention, employing four deformations along each side of the seal;

Fig. 5 shows a side elevation of the strap ends and seal illustrated in Fig. 4; and

25 Fig. 6 shows an enlarged transverse section on the line 6—6 of Fig. 4.

As illustrated in the drawings, the flat steel strap 10 which may have been passed around a package and drawn taut, for example, is arranged with one end 10^a overlapping the other end 10^b and these overlapping ends are secured together by the strap seal 11 which is in the form of a sleeve enclosing portions of the overlapping ends

30 of the strap. This seal may have the initial form of a sleeve through which the ends 10^a and 10^b of the strap are threaded or it may have the form of a channel so that the overlapping ends of the strap may be placed

40 within the channel after which the side walls or edge portions 11^a of the channel are bent inwardly into contact with one side of the strap as shown, for example, in Fig. 3. The

45 interlocking connection between the ends of the strap 10 and the sleeve 11 is formed by shearing the edges of the strap and seal inwardly at right angles to the length of the strap. According to the present invention, a plurality of deformations are formed preferably by a plurality of pairs of cuts, and in

50 the embodiment illustrated in Figs. 1, 2 and 3 of the drawings, three such pairs of cuts are shown at each side of the seal and strap.

55 The shearing of the edges of the strap and seal is preferably effected by a suitable sealing device having shearing dies for engaging the edges of the seal and deflecting portions thereof transversely to form a projecting lug between the cuts of each pair, such, for example, as the sealing device described and claimed in the co-pending application of John Ekern Ott, Serial No. 588,319, filed January 23, 1932.

60 In the form illustrated in Figs. 1, 2 and 3, the seal has three pairs of deformations 12

extending inwardly from the edges of the seal, with the deformations of each pair located opposite each other. Each deformation 12 is formed by cutting or shearing the edges of the strap and seal inwardly along two spaced lines 13 and 14 and bending the intervening material downwardly to form an intervening deflected lug 15. In forming these deformations, the cuts 13 are preferably made deeper than the cuts 14 so that the inner margin 16 of the deflected lug or deformation extends at an angle to the longitudinal axis of the strap. The longer cuts 13 of the deformations 12 of each pair are located in alignment with each other so that the inner margins of the deformations of each pair converge longitudinally of the strap. Where three pairs of deformations are used, it is found that the joint has greater strength if the inner margins of the lugs of one pair converge longitudinally in one direction while the inner margins of the lugs of the other two pairs converge longitudinally in the other direction.

The nature of the interlocking joint which is formed by the cuts 13 and 14 is shown particularly in Fig. 3, where it will be seen that the formation of the lugs 15 causes the edge portions of the overlapped ends 10^a and 10^b of the strap to be deflected downwardly along with the looped edge portions of the sleeve 11. The extent of the downward deflection of these portions of the strap and seal should preferably be sufficient to cause the edges of the uppermost strap end to overlap the edges of the lower strap end and also the lower wall of the enclosing sleeve and, in order to obtain this result, it will be apparent from an examination of Fig. 3 that the lower strap end and the lower wall of the seal should preferably be cut inwardly from the edge of the seal to a greater extent than the upper strap end and the lower wall of the seal. This results in the bending of the edge portions of the seal and of the edge portions of the strap about lines which lie in planes 17 which are inclined to the surfaces of the seal and it causes the lugs to have an inclination downwardly toward the cuts 13, longitudinally of the strap, as shown in Fig. 2, in addition to the inclination of their inner margins with respect to the longitudinal axis of the strap. The possibility of obtaining the maximum interlocking effect, that is, the interlocking of the transverse surface over the maximum area, is increased by increasing the depth of the cuts since the use of deeper cuts permits the edges of the upper strap end between a pair of cuts to be bent downwardly to such an extent that it overlaps both the lower strap end and the lower wall of the seal, as shown in Fig. 3. The extent to which the cuts should be extended inwardly from the edge of the seal should vary directly with the width of the strap and it can be deter-

mined readily by trial which depth of cut is most suitable for a particular width of strap. While the extent of the overlapping areas of the interlocking portions of the seal 5 and strap along the lines of the cuts may be increased by increasing the depth of the cuts, a cut of undue depth tends to weaken the joint.

For illustration, it has been found that 10 very satisfactory results are obtained in uniting the ends of a two inch strap by means of the present invention if the distance between the inner ends of the cuts 13 is made substantially 1-46/64 inches while the distance 15 between the inner ends of the cuts 14 is made 1-51/64 inches. With cuts of this depth and with the inner margins of all of the lugs of all three pairs inclined in the same direction, the joint has a strength of about 84% of that 20 of the uncut strap. When the lugs of one pair are reversed, however, so that their inner margins are inclined in a direction opposite to the inclination of the inner margins of the other two pairs, it is found that the 25 strength of the joint is greatly increased. For example, with the last-mentioned arrangement of the inner margins of the lugs and with the inner ends of the cuts 13 spaced apart a distance of 1-41/64 inches and with 30 the inner margins of the cuts 14 spaced apart a distance of 1-48/64 inches, it is found that the joint has a strength of about 94% of the strength of the uncut strap. While the joint between any pair of inwardly extending cuts 35 13 or 14 may not have a strength acting alone approximating any of the percentages of strength mentioned above, it is found that when a plurality of pairs of cuts are formed in the same seal, the composite strength is 40 greatly increased as compared with that of a single pair of cuts on each side of the strap and this increase is most marked when the inner margins of the lugs of one pair are directed oppositely to the inner margins of the 45 lugs of the other pair. The strength of the joint with one pair of oppositely located lugs or with a plurality of pairs of oppositely located lugs, is increased by making the cuts of unequal depth on opposite sides of each 50 lug, as compared with the strength which would be obtained if these cuts were of equal depth. It is therefore possible by means of the present invention to obtain a joint approximating the strength of the uncut strap 55 by employing a plurality of similar deformations in the edges of the strap seal but, preferably, with the lugs of one pair directed oppositely to those of the other pairs. By means of this invention, therefore, it is possible 60 to reinforce a package or to combine a number of packages together by straps which are much smaller in size than those heretofore employed because it has been necessary heretofore to use straps which were 65 large enough to insure the required strength

at their weakest points, that is, the points where the seals were located and these points have often only had a strength of 60% of that of the uncut strap.

In Figs. 4, 5 and 6 of the drawings, there is illustrated a modification of the invention in which the joint is formed by employing four deformations along each edge of the strap and seal. In this embodiment, the strap 70 20 has one end 20^a thereof overlapping the other end 20^b and these ends are enclosed by a tubular seal 21. The seal 21 may have the strap ends threaded therethrough or it may be in the form of a channel initially and then have its side walls 21^a bent inwardly to overlap the overlapping strap ends, as shown in Fig. 6. In this instance, there are four deformations 22 along each side of the seal 75 and each deformation is formed by cutting or shearing the strap and seal transversely along the lines 23 and 24, of unequal depth, and bending the intervening material downwardly to form a deflected lug 25. As in the form of the invention previously described, the cuts 23 are preferably made deeper than 80 the cuts 24 so that the inner margins 26 of the lugs or deformations are inclined to the longitudinal axis of the strap. The lugs are located opposite to each other in pairs so that the inclined margins 26 of opposite lugs converge longitudinally of the strap. In order to 85 obtain the greatest strength, the inner margins of the lugs of two pairs are preferably arranged to converge in a direction opposite to that of the inner margins of the lugs of the other two pairs.

As in the form of the invention first described, the depth of the cuts in the arrangement shown in Figs. 4, 5 and 6, to obtain the best results, will vary directly with the width 90 of the strap. For illustration, it is found that with the inner margins of the lugs of two pairs directed oppositely to the inner margins of the lugs of the other two pairs and with the inner ends of the cuts 23 spaced apart a distance of 1-44/64 inches, while the inner ends of the cuts 24 are spaced apart a distance of 1-53/64 inches, the joint has a strength of about 96.8% of that of the uncut 95 strap. On the other hand, if the inner margins of the lugs are all directed in the same direction, the strength of the joint is considerably less than the figures just given, although substantially greater than the strength of a joint made by a single pair of oppositely located lugs for a joint using the 100 same number of pairs of lugs in which the cuts are all extended inwardly to the same depth.

Although two forms of the improved strap seal and one method of forming the same have been described by way of illustration, it will be seen that the seal may be made in various forms and constructed by various methods 105 within the scope of the appended claims.

I claim:

1. A strap seal comprising overlapped strap ends and a sleeve embracing them, marginal portions of said sleeve and the enclosed strap ends being deflected to form a plurality of similar transversely directed deformations of equal depth along each edge of the sleeve, said deformations having their inner margins inclined to the longitudinal axis of the strap.
2. A strap seal comprising overlapped strap ends and a sleeve embracing them, marginal portions of said sleeve and the enclosed strap ends being deflected to form a plurality of similar transversely directed deformations of equal depth along each edge of the sleeve, said deformations being located opposite each other in pairs with the inner margins of the deformations of each pair converging longitudinally of the strap.
3. A strap seal comprising overlapped strap ends and a sleeve embracing them, marginal portions of said sleeve and the enclosed strap ends being deflected to form a plurality of similar transversely directed deformations of equal depth along each edge of the sleeve, said deformations being located opposite each other in pairs with the inner margins of the deformations of each pair converging longitudinally of the strap, the inner margins of the deformations of one pair being arranged to converge in a direction opposite to the convergence of the inner margins of other pairs.
4. A strap seal comprising overlapped strap ends and a sleeve embracing them, marginal portions of the sleeve and enclosed strap ends being sheared transversely of the strap to form along each edge of said sleeve a plurality of transversely projecting lugs, the cuts on the opposite sides of each lug being of unequal depth and of the same depth as the cuts on the opposite sides of the other lugs.
5. A strap seal comprising overlapped strap ends and a sleeve embracing them, marginal portions of the sleeve and enclosed strap ends being sheared transversely of the strap to form along each edge of said sleeve a plurality of transversely projecting lugs, the cuts on the opposite sides of each lug being of unequal depth and of the same depth as the cuts on the opposite sides of the other lugs, said lugs being located opposite each other in pairs with the inner margins of the lugs of one pair converging longitudinally of the strap in a direction opposite to the convergence of other opposite lugs formed by said cuts.
6. A strap seal comprising overlapped strap ends and a sleeve embracing them, marginal portions of the sleeve and enclosed strap ends being sheared transversely of the strap to form along each edge of said sleeve a plurality of transversely projecting lugs, the cuts

on the opposite sides of each lug being of unequal depth and of the same depth as the cuts on the opposite sides of the other lugs, the depth of each cut increasing progressively from one surface of the seal to the other opposite parallel surface.

7. A strap seal comprising overlapped strap ends and a sleeve embracing them, the marginal portions of the sleeve and enclosed strap ends being sheared transversely of the strap to form transversely projecting lugs located at opposite edges of the seal, the cuts on opposite sides of each lug being of unequal depth, the inner margins of said lugs converging longitudinally of the strap.

8. A strap seal comprising overlapped strap ends and a sleeve embracing them, said sleeve and strap ends being provided with spaced cuts extending transversely thereof at the margin of the seal to form an intervening lug which is bent transversely to the plane of the strap, the cuts at the opposite edges of said lug being of unequal depth.

In testimony whereof, I have subscribed my name.

JOHN EKERN OTT.
